UNITED STATES PATENT OFFICE

HARRY J. BOSWORTH, OF CHICAGO, ILLINOIS, ASSIGNOR TO HARRY J. BOSWORTH COMPANY, OF CHICAGO, ILLINOIS, A CORPORATION OF ILLINOIS

DESIGN FOR AN ADVERTISING TOOTHBRUSH DISPLAY STAND

Application filed September 19, 1931. Serial No. 41,153. Term of patent 7 years.

To all whom it may concern:

Be it known that I, HARRY J. BOSWORTH, a citizen of the United States, residing at Chicago, in the county of Cook and State of Illinois, have invented a new, original, and ornamental Design for an Advertising Tooth Brush Display Stand, of which the following is a specification, reference being had to the accompanying drawing, forming a part thereof.

The figure is a perspective view of an advertising tooth brush display stand showing my new design. It is to be understood that the tooth brush forms an inseparable part of the display stand.

I claim:

The ornamental design for an advertising tooth brush display stand, as shown and described.

In witness whereof, I hereunto subscribe my name this 28th day of August, 1931.

HARRY J. BOSWORTH.
